FIG 4

UNITED STATES PATENT OFFICE

JAMES G. PORTTEUS, OF TOLEDO, OHIO

CONTAINER AND ROLLER OF CIGARETTES

Application filed October 14, 1931. Serial No. 568,682.

My invention relates to containers for retaining cigarettes to be carried from place to place to prevent their becoming broken or mis-shapened. The invention particularly relates to a container, the walls of which cooperate with a flexible sheet element located within the container to shape and form loose tobacco materials into a usable cigarette shape.

10 The invention has for its object to provide a cigarette container or case, which may be easily and conveniently carried in the apparel of the user, the walls of which are formed so as to cooperate with members supported within the container to form a cigarette. The invention has for its particular object to provide a relatively thin container or case in which is located a movable member and a flexible sheet element which together cooperate with the walls of the container to form and shape loose compactible materials, such as tobacco, into cigarette shape. The invention provides a simple construction of related members for forming a compactible material into cigarette shape which may be manufactured at a low cost and have an attractive appearance.

20 The invention consists in other features and advantages which will appear from the following description and upon examination of the drawing. Structures containing the invention may partake of different forms and may be varied in their details and still embody the invention. To illustrate a practical application of the invention, I have selected a case for producing cigarettes embodying the invention as an example of the various structures, and the details of such structures, that contain the invention and shall describe the selected structure hereinafter, it being understood that variations may be made and that certain features of my invention may be used to advantage without corresponding use of other features, and without departing from the spirit of the invention. The particular structure selected is shown in the accompanying drawing.

25 Fig. 1 is a perspective view of the case and illustrates the operable members prepara-

tory to forming a cigarette. Fig. 2 is a view of a longitudinal cross section of the case. Fig. 3 is a cross sectional view and illustrates the positions of component parts of the device when not in use. Fig. 4 is a view of a transverse section of the case.

30 The convenience of making cigarettes, as desired has not heretofore been accompanied by a convenient means for carrying the finished articles without the use of other containers and enclosing within the container the means for making the cigarettes. By the use of my invention, cigarettes may be produced as the user desires and a supply located in the container. A movable member or plunger is associated with a flexible sheet member, both of which are located within the container, so that, upon movement of the plunger within the confines of the case, the sheet member will be operated to exert a rolling compressing force on the materials of which the cigarette is formed and produce a finished cigarette at the completion of the travel of the plunger. The plunger and flexible sheet may be subsequently located so as to provide ample room in the container for retaining a number of completed cigarettes.

35 In the form of construction shown in the drawing, the cigarettes are formed by movement of a plunger 1 in cooperation with a flexible sheet 2 and within the confines of a container 3. The container 3 may be provided with beaded portions or channels 4 formed in the sides 5 of the container to guide and support the cross-head 9 of the plunger in reciprocal movement through the container. The plunger 1 may have a suitable handle 8 for manipulation of the cross-head 9 which is connected to the draw bar by legs or guides 7.

40 The cross-head 9 of the draw bar 1, which cooperates with the flexible sheet 2 in the cigarette shaping operation, may be formed substantially oval in cross section to prevent jamming or pinching of the sheet between the cross-head and the walls of the container in compressing and forming the cigarettes. The cross-head 9 of the bar 1 guides the movement of the sheet 2 so that materials

for forming the cigarette, located in the sheet, will be rolled into the desired form and compressed by the pressure exerted by the sheet 2, in conjunction with the cross-head 9 and walls of the container.

In order to secure the ends of the sheet 2 within the container and to obtain a desired tension of the sheet, as well as to prevent slippage or increasing slackness in subsequent operations, the ends 10 of the sheet are looped about wire pins 6. The flexible sheet 2 may then be secured within the container by crimping struck up edge portions of the container 3 over the looped ends 10 and the pins 6. One of the ends of the sheet is secured in the rear wall of the container, as at 12, while the opposite end is secured near the front wall in the bottom, as at 13. Thus, the sheet 2 is securely located in the container 3 in opposition so that it may be engaged by the cross-head 9 of the draw bar 1 as the cross-head is moved through the container.

In order to position the cigarette forming materials upon the flexible sheet 2, so that a satisfactory assembly of the materials may be obtained, the bottom wall 11 of the container has a pocket or recess 14 close to one end of the container. A portion of the flexible sheet 2 may be placed so as to lie along the surface of the pocket 14, thus forming a slackened portion 15 for receiving loose tobacco 16. Upon movement of the cross-head 9 over the recess, the sheet 2 will be engaged by the cross-head so as to wrap the slackened portion 15 about the tobacco and raise it out of the pocket 14 and onto the surface of the bottom 11 of the container 3. As the cross-head continues to draw the slackened portion 15 of the sheet 2 across the surface of the bottom 11 the tobacco 16 will be compressed and rolled into a compact mass about which a suitable sheath of paper 17 may be secured to form a cigarette. The paper 17 may be placed on the sheet 2 preferably so that one edge lies on a portion of the sheet located over a depressed or concave area 18 formed in the bottom wall 11. The area 18 is located adjacent the pocket 14 so that the tension of the sheet will be of lesser magnitude relative to the compressed tobacco and to permit the insertion of the edge of the paper 17 between the cross-head 9 and the sheet 2. Thus, as portions 15 of the sheet 2 are moved by the cross-head 9 of the bar over the bottom wall 11 of the container, the materials will be compactly rolled into cigarette form. A suitable opening 19 may be provided proximate to one end of the container and the sheet, through which the cigarette may be delivered upon completion.

The opening 19 of the case may be closed by a suitable cover 20 which may be hingedly connected to the container as at 22. The

cover 20 operates with the pocket 14, as supporting legs for the container during the forming operation so that the handle 8 of the draw bar 1 will be conveniently located above any surface on which the container is placed. Suitable ears 21 may be formed on the cover and be bent towards each other to provide resilient retaining members for holding the cover in a closed position. The wall 25 of the container may be hingedly connected to the container 3, as at 29, and has flanged portions 26 which extend over the edges of the channels 4 when the wall 25 is located so as to close the container. The wall 25 may also have flanges 27 for extending over portions of the handle 8 and thus retain the plunger 1 within the container 3 and prevent its outward movement when the case is being carried. To provide for suitable location of the handle 8 when the cover 25 is closed, the wall of the container may be provided with a groove 30 for receiving major portions of the body of the handle.

When the cover 20 is closed, the interior of the container may be filled with a supply of cigarettes. The area within the container is unobstructed by the operated members, since when the handle 8 is located in the groove 30, the cross-head 9 of the draw bar 1 will be positioned against the rear wall, allowing the flexible sheet 2 to lie flat against the bottom wall 11 and the chamber thus formed may be used advantageously as a place for storing cigarettes.

I claim:

1. In a container for cigarettes, the side walls of the container having channels, a U-shaped handle member slidably supported in the channels, a cross head connected to the handle and adapted to be reciprocated through substantially the entire length of the container in a plane parallel to the plane of the major portion of the bottom wall of the container, and a flexible element connected to the container at points proximate to the ends of the stroke of the cross head, the flexible sheet element being adapted to be slidably engaged by the cross head, portions of the flexible sheet element being adapted to receive cigarette materials and located between the cross head and the bottom wall of the container for compressing the cigarette materials into cigarette form.

2. In a cigarette container, the side walls of the container having outwardly projecting bead portions, the front wall of the container having an inwardly projecting bead portion, a U-shaped handle, the legs of the U-shaped handle being slidably supported in the outwardly projecting bead portions of the side walls, the web of the U-shaped handle being adapted to be located in the inwardly projecting bead portion of the front wall, a cover hingedly connected to

the rear wall of the container, the cover having flanges, the flanges being adapted to engage the web of the U-shaped handle to maintain the web of the handle in the inwardly projecting bead portion of the front wall, the bottom wall of the container having a recess formed at one end and an opening formed at the other end, a cover hingedly connected to the bottom wall for closing the said opening and adapted to support the container when open, a pair of ears extending from the second named cover for resiliently engaging the side walls of the container, a cross head connected to the handle and adapted to be reciprocated through substantially the entire length of the container in a plane parallel to the plane of the major portion of the bottom of the container, and a flexible sheet element connected to the interior of the said back and bottom wall of the container at points proximate to the ends of the stroke of the cross head, the flexible sheet element being adapted to be slidably engaged by the cross head, portions of the flexible sheet element being adapted to be located in the recess of the bottom wall of the container for receiving cigarette materials, said portions of the flexible sheet element being adapted to be compressed between the cross head and the bottom wall of the container for compressing the cigarette materials into cigarette form.

In witness whereof I have hereunto signed my name to this specification.

35 JAMES G. PORTTEUS.
